UNITED STATES PATENT OFFICE

EDWIN O. BARSTOW, OF MIDLAND, MICHIGAN, ASSIGNOR TO THE DOW CHEMICAL COMPANY, OF MIDLAND, MICHIGAN, A CORPORATION OF MICHIGAN.

METHOD OF MANUFACTURING ARSENATE OF LEAD.

1,184,693.

Specification of Letters Patent.

Patented May 23, 1916.

No Drawing.

Application filed August 1, 1912. Serial No. 712,677.

To all whom it may concern:

Be it known that I, EDWIN O. BARSTOW, a citizen of the United States, and a resident of Midland, county of Midland, and State of Michigan, have invented a new and useful Improvement in Methods of Manufacturing Arsenate of Lead, of which the following is a specification, the principle of the invention being herein explained and the best mode in which I have contemplated applying that principle, so as to distinguish it from other inventions.

The present method or process may be regarded as a modification of the general process of manufacturing lead arsenate presented in my co-pending application filed even date herewith and since issued into Patent No. 1,169,114, dated January 25 1916.

In this case, as in such general process, the mode of procedure involved is equally applicable to the manufacture of other insoluble arsenates than lead arsenate, as for example, zinc, iron and barium arsenates.

The process constituting the present invention, then, consists of the steps hereinafter fully described, and particularly pointed out in the claims.

The following description sets forth in detail one approved mode of carrying out the invention, such disclosed mode, however, being merely illustrative of the various ways in which the principle of the invention may be used.

The general method of procedure involved in the improved process under consideration consists in oxidizing an arsenic derivative to arsenic acid by means of a halogen; providing a compound to form a haloid with such halogen reagent; and adding a suitable compound of the metal, the arsenate of which is desired as a final product. As previously indicated, the process is applicable to any metal capable of being precipitated as such arsenate from its corresponding soluble salt, such as its haloid. Commenting further on this statement relative to the general mode of procedure, it should be noted that it is immaterial so far as the steps in the process are concerned, whether they be performed in the sequence just indicated, or in part or in whole, simultaneously; and, as will now be explained, in the present modification of such general process, the base for forming a haloid with the halogen reagent is added first, and the halogen for oxidizing the

arsenic derivative is added subsequently. In carrying out such process, white arsenic, or arsenius oxid (As_2O_3), is dissolved in a solution of soda ash, or equivalent alkali, and, inasmuch as no carbonic acid gas is apparently evolved, the reaction would seem to be correctly represented by the following equation:

The exact intermediate phenomena, however, are immaterial both here and in such other reactions as may be indicated subsequently; it being the end result of course that is of interest. The next step in the process is to chlorinate the solution thus obtained, as a result of which a solution of arsenic acid and common salt may for convenience in representation be assumed to be obtained, as exhibited by the following reaction:

Although it is probable that arsenic acid, hydrochloric acid, sodium arsenate and sodium chlorid are all present, as well as free ions of sodium, chlorin and the arsenate radical, AsO_4^{3-} .

Where, as in the specific instance assumed for illustrative purposes, it is lead arsenate that is wanted, the oxid of this metal is then stirred into the solution. The reaction occurring may be represented as follows, assuming the signification reagent solution to be arsenic acid:

Instead of the lead oxid, the hydrate, carbonate, or basic carbonate of lead may be used as per the following reactions:

Preferably, the amount of soda ash used in preliminary forming the sodium arsenite, is somewhat greater than the actual requirements of the chlorin subsequently added. Conversely the amount of lead oxid,

or other lead compound, that is added, will preferably be less than an equivalent of the free acid in the solution.

As an alternative to the reactions given above to represent what happens when the sodium arsenite is chlorinated, and an oxygen derivative of lead thereupon added to the resulting solution, the following equations are given:—

It is immaterial, so far as the reaction with the lead oxid is concerned, whether arsenic acid, or hydrochloric acid, or both, be assumed to be present; and in determining the amount of such oxid to be added, it suffices to determine the amount of free acid present without inquiring as to whether it is one or the other.

The mixture obtained by the last described step is next dropped onto a filter and washed with water leaving the lead arsenate, which is chiefly the acid lead arsenate behind. The filtrate and washings, containing sodium chlorid, sodium arsenate and free acid are, however, saved, and sodium carbonate is added thereto, until the acid is at least neutralized. Finally lead chlorid solution is run in to precipitate the normal lead arsenate, $\text{Pb}_3(\text{AsO}_4)_2$, the reaction for which may be thus represented—

40 The step last described for the formation of lead arsenate by the reaction of lead chlorid, on sodium arsenate may itself be regarded as a method of making the lead arsenate independently of any antecedent steps. Such reaction is, however, presented here as a part of the general process only.

The preliminary reaction, that of treating arsenious oxid with soda ash may be conducted satisfactorily in an open tank or tub into which these materials, together with water are charged; while the chlorination will be conducted in stone-ware, coke-packed chlorination towers, the mixture to be chlorinated being pumped continuously over said towers. The lead oxid, or equivalent oxygen derivative of the metal of which the arsenate is desired, is added to the solution of arsenic acid and sodium oxid in a wooden tank provided with a suitable stirrer, the solution being sufficiently concentrated to provide a mixture of the proper consistency. It has been discovered that by sufficiently prolonging the stirring, 65 the lead arsenate may be made from the

solid lead oxid, hydrate, carbonate, or basic carbonate, despite the fact that, at first sight, it would seem that this reaction could not be carried to completion, because the resulting product being solid, the lead oxid would not be reacted upon, but particles of it would be inclosed in an impervious coating of the lead arsenate. On subjecting the liquid, however, to a sufficiently prolonged stirring, or agitation, this tendency has been successfully overcome as above indicated.

The oxygen derivatives of lead, which are suitable for use as compounds of that metal for reacting with arsenic acid to form lead arsenate, have already been indicated. The term "oxygen derivative" is intended, therefore, to connote such equivalents of lead oxid in addition to those which have been specifically named, as will form the compound in question under the conditions surrounding the reaction. By way of general comment, it should further be noted that both the acid lead arsenate PbHAsO_4 , and the normal arsenate $\text{Pb}_3(\text{AsO}_4)_2$, are commonly known to the trade as arsenate of lead. The latter term is accordingly to be understood as used herein in this general sense, and not as referring specifically to either of the two arsenates named except where the contrary is indicated. So, too, a soluble alkaline earth arsenate may be used instead of the alkaline arsenate hereinbefore specified, as the preferred soluble article, as will be readily understood, and such equivalent is intended to be connoted by the term "alkaline" as herein employed.

It is proper to repeat, by way of conclusion, that the several equations which have been heretofore referred to as expressive of the different reactions involved, are presented as illustrative, merely of the principal phenomena. They do not, however, necessarily represent all of the reactions that actually occur, and should be understood as indicating how the desired end-product is derived, rather than the exact intermediate steps leading thereto. From the standpoint of the manufacturer or practical chemist, indeed, it might be better to represent the whole series of detailed reactions pertaining to each particular process or sub-process described above, as a single comprehensive reaction, in which only the starting materials and observed end-products are given. Thus, for example, the specific mode of operation herein claimed may be represented as follows:—

In other words, so far as the commercial operation of the process in hand is concerned, it may be regarded as consisting in a reaction between white arsenic, soda ash, 125

chlorin and lead oxid. As has already been indicated, the present process is limited to that specific aspect of the general reaction just described, in which soda ash is combined with the white arsenic to form a soluble arsenite before the chlorination step.

Other modes of applying the principle of my invention may be employed instead of the one explained, change being made as 10 regards the process herein disclosed, provided the step or steps stated by any one of the following claims or the equivalent of such stated step or steps be employed.

I therefore particularly point out and distinctly claim as my invention:—

1. The method of making an insoluble metallic arsenate, which consists in treating a solution of an arsenate with a halogen; and adding to such treated solution a compound of the metal of which the arsenate is desired, such compound being adapted to produce such arsenate upon being added to a solution of arsenic acid.

2. The method of making an insoluble metallic arsenate, which consists in treating, in the presence of water, an alkaline arsenate with chlorin; and adding to the resulting product a compound of the metal of which the arsenate is desired, such compound being adapted to produce such arsenate upon being added to a solution of arsenic acid.

3. The method of making an insoluble metallic arsenate, which consists in treating, in the presence of water, sodium arsenite with chlorin; and reacting with the product of an oxid of the metal of which the arsenate is desired.

4. The method of making lead arsenate, which consists in treating, in the presence of water, an arsenite with a halogen; and reacting, with the resulting product on an oxygen derivative of lead, adapted to produce such arsenate upon being added to a solution of arsenic acid.

5. The method of making lead arsenate, which consists in treating, in the presence of water, an alkaline arsenite with chlorin; and reacting with the resulting product on an oxygen derivative of lead adapted to produce lead arsenate upon being added to a solution of arsenic acid.

6. The method of making lead arsenate, which consists in treating, in the presence of water, an alkaline arsenite with chlorin; and reacting with the resulting product on lead oxid.

7. The method of making lead arsenate, which consists in treating a solution of sodium arsenite with chlorin; and then stirring the resulting solution with lead oxid.

8. The method of making lead arsenate, which consists in mixing arsenious oxid, sodium carbonate and water to form a solu-

tion of sodium arsenite; chlorinating such solution; and reacting with the resulting solution on an oxygen derivative of lead adapted to produce lead arsenate upon being added to a solution of arsenic acid.

9. The method of making lead arsenate, which consists in mixing arsenious oxid, sodium carbonate and water to form a solution of sodium arsenite; treating such solution with chlorin; and then stirring the resulting solution with lead oxid.

10. The method of making an insoluble metallic arsenate, which consists in treating, in the presence of water, an alkaline arsenite with chlorin; stirring the resulting solution with an oxygen derivative of the metal of which the arsenate is desired, such derivative being adapted to produce such arsenate upon being added to a solution of arsenic acid, whereby the arsenate of said metal is obtained, the amount of such oxygen derivative being insufficient to combine with all the free acid present; separating out such arsenate; adding an alkali to the residual solution; and then adding a solution of the chlorid of said metal thereto.

11. The method of making an insoluble metallic arsenate, which consists in mixing arsenious oxid, sodium carbonate and water to form a solution of sodium arsenite; chlorinating such solution; stirring the resulting solution with the oxid of the metal of which the arsenate is desired, whereby the arsenate of said metal is obtained, the amount of such oxid being insufficient to combine with all the free acid present, filtering out such arsenate; adding sodium carbonate to the filtrate; and then adding a solution of the chlorid of said metal thereto.

12. The method of making lead arsenate, which consists in treating a solution of sodium arsenite with chlorin; stirring the resulting solution with lead acid, whereby lead arsenate is obtained, the amount of such lead acid being insufficient to combine with all the free acid present; separating out such arsenate; adding an alkali to the residual solution; and then adding lead chlorid solution thereto.

13. The method of making lead arsenate, which consists in mixing arsenious oxid, sodium carbonate and water to form a solution of sodium arsenite; chlorinating such solution; stirring the resulting solution with lead acid, whereby lead arsenate is obtained, the amount of such lead acid being insufficient to combine with all of the free acid present; filtering out such arsenate; adding sodium carbonate to the filtrate; and then adding lead chlorid solution thereto.

14. In a method of making an insoluble metallic arsenate, the steps which consist in stirring a solution of arsenic acid with an oxygen derivative of the metal of which the arsenate is desired, such derivative being

- adapted to produce such arsenate upon being added to a solution of arsenic acid, whereby the acid arsenate of said metal is obtained, the amount of such oxygen derivative being insufficient to combine with all the free acid present; separating out such arsenate; adding an alkali to the residual solution; and then adding a solution of the chlorid of said metal thereto.
- 10 15. In a method of making an insoluble metallic arsenate, the steps which consist in stirring a solution of arsenic acid with the oxid of the metal of which the arsenate is desired, whereby the arsenate of said metal is obtained, the amount of such oxid being insufficient to combine with all of the acid present; filtering out such arsenate; adding sodium carbonate to the filtrate; and then adding a solution of the chlorid of said metal thereto.
16. In a method of making lead arsenate, the steps which consist in stirring a solution of arsenic acid with lead oxid, whereby acid lead arsenate is obtained, the amount of such oxid being insufficient to combine with all of the acid present; separating out such arsenate; adding an alkali to the residual solution; and then adding lead chlorid solution thereto.
17. In a method of making lead arsenate, the steps which consist in stirring a solution of arsenic acid with lead oxid, whereby acid lead arsenate is obtained, the amount of such oxid being insufficient to combine with all the free acid present; filtering out such arsenate; adding sodium carbonate to the filtrate; and then adding lead chlorid solution thereto.

Signed by me this 27th day of July, 1912.
